UNITED STATES PATENT OFFICE.

WILLIAM J. P. MOORE, OF NEW YORK, N. Y.

DEMOUNTABLE RIM.

1,249,452.

Specification of Letters Patent Patented Dec. 11, 1917.

Application filed March 20, 1916. Serial No. 85,370.

To all whom it may concern:

Be it known that I, WILLIAM J. P. MOORE, a citizen of the United States, residing at New York, in the county of New York and State of New York, have invented certain new and useful Improvements in Demountable Rims, of which the following is a specification, reference being had therein to the accompanying drawing.

10 My present invention refers to certain new and useful improvements in demountable rims for wheels intended chiefly for use with automobiles and similar vehicles, although adapted for use with any kind of machinery where a removable rim is employed. The object of the invention is to provide a simple and economical construction and one which may be readily handled in the process of removing and replacing the parts. With 15 this and other objects in view, the invention comprises essentially the combination of a wheel body having a transversely-curved edge and a removable rim having an inner transversely-curved edge engaging the wheel; also the combination of a felly or a band surrounding the felly whose peripheral edge is transversely curved, or is the segment of a sphere, and a demountable rim encircling the same whose inside peripheral edge is the segment of a corresponding sphere, the segment in the one case being convex and in the other concave, but being concentric with each other, and the center being the center of the wheel and of 20 its axle and hub; and further, the invention comprises numerous details and peculiarities in the construction, arrangement, and combination of the parts, substantially as will be hereinafter described.

40 In the accompanying drawing illustrating my invention:

Figure 1 is a cross-section of my improved demountable rim at one point in its periphery;

45 Fig. 2 is a cross-section at a point in the periphery directly opposite the section in Fig. 1 so that these two figures taken together make up a cross-section of the entire wheel with the exception of the central member;

50 Fig. 3 is a diagrammatic cross-sectional view of a wheel provided with my improved rim, and shows how the rim may be shifted off and on the wheel;

55 Fig. 4 is a cross-section of a modified form of the invention;

Fig. 5 is a side elevation of my improved demountable rim shown as applied to a wheel;

Fig. 6 is a cross-section of another modified form of the invention.

Similar characters of reference designate corresponding parts throughout the different figures of the drawing.

Referring first to Figs. 1 and 2, 7, 7 denote the flanged sections of a clincher rim, holding the beads of the shoe 9 of a resilient tire, 30 being the inner tube and 10 the air valve. These clincher sections 7 encircle the split band or ring 1 to which they are connected by means of the wires 8 let into grooves in sections 7 and ring 1, as shown, said ring 1 having parallel flanges 2, 2, the edges 12 of which are transversely curved and are preferably segments of a sphere struck from the center of the wheel-hub or axle, that is to say the center of the rim of the wheel; and said edges of flanges 2, 2 are obviously concave.

The wheel body proper is composed of a fixed rim 3, having parallel flanges 4, 4, and a pair of lateral disks 5 that are attached to the fixed rim and also to a central hub, as 21. The method of attaching the disks 5 to the parallel flanges 4 may vary within wide limits, and that shown, consisting of inturning the outer edges of disks 5 and causing them to enter suitable grooves in members 4 and holding them therein by rings 6 that are applied in a heated state and allowed to cool and weld the parts together, is only one of many that may be adopted. The edges 11 of the flanges 4, 4, opposite to the edges 12 of flanges 2, 2 are segments of a sphere struck from the same center as the sphere having segments 12, so that the two spheres are concentric, and said edges 11 being convex; and consequently the outer ring 1 is readily movable over the fixed rim 3, when the two parts are loosely applied to each other and are being moved in relation to each other as indicated in the positions shown in Fig. 3. The skeleton structure of a removable ring having side flanges and a fixed rim having side flanges, which flanges are in contact, the convex spherical segments fitting neatly within the concave spherical segments, provides a hollow box-like member which is light and strong; but it is evident that the shape and size of the parts may vary within wide limits and engaging parts may be solid in cross-section if

100

105

110

desired, as shown in Figs. 4 and 6, which I shall presently describe. When such flanged fixed and removable rims are used, it will be evident that the curvature of the spherical segments will be comparatively small, as the flanges are narrow and the spheres are of substantial size, but this will not affect the easy engagement of the segmental faces when they are brought into contact, as the curvature is definite and pronounced enough to provide for that, as indicated by the curved dotted lines in Figs. 1 and 2 which follow the arcs of the spheres, whose centers are at the center of the hub 21, shown in Fig. 5, but not in Figs. 1 and 2, as the parts in the latter figure are on such an enlarged scale.

Assume now that the demountable rim is on the wheel. This means that the parts are in the relation shown in Figs. 1 and 2, and in full lines in Fig. 3, that is to say the edges 11 and 12 of the fixed and removable rims are concentric with each other, are therefore in contact through their entire surface, and the outer sides of the flanges 2 and 4 are exactly flush with each other, so that there is no wedging or binding action of these segmental edges with each other, but they are simply in easy-fitting contact. It is desirable to hold them so while the rim is on the wheel, and this I do by means of a series of transverse bolts 14, say six or more, although of course any number, having heads 15 and screw-threaded sections 17, carrying nuts 16. These bolts 14 pass through transverse holes cut, as shown in Fig. 2, so as to be partly in the flanges 2, 2 and partly in the flanges 4, 4, that is to say, running through the two meeting edges 11 and 12 on one side, and also through the other two meeting edges 11 and 12 on the other side, so that the edges being relatively positioned as I have stated, the effect of tightly screwing up the nuts 16 will be to tightly lock the parts in this position, for as the head 15 of each bolt bears against a part of one flange 2 and a flush part of the adjacent flange 4, and as the nut 16 on each bolt bears against a part of the other flange 2 and a flush part of the adjacent flange 4, it is manifest that by screwing up the nuts on the bolts the fixed and removable rims will be securely clamped in their interspherical position, which will allow the wheel to operate as desired and the rim thereof, which is now firmly secured, to perform its function of carrying the resilient tire. Further, the bolts, as they pass through holes that are in both the fixed and removable rims, prevent any circumferential movement of the removable rim on the fixed rim, that is, any creeping which might displace the rim.

When the occasion arises to demount the tire, the bolts 14 will first be removed. The

removable rim can then be swung off the fixed rim, by turning said removable rim on its center as shown in dotted lines in Fig. 3 and cause the rim to follow a path indicated by the dotted circle in said figure. 70 But the rim cannot be slid over the convexity of the fixed rim flanges 4, 4 so long as said convexity retains its true character of the segment of a circle and the concavity of the removable rim flanges does the same, 75 and hence I find it necessary to flatten one or the other to provide means for moving one across or over the other. This flattening may take place at one or more points and I preferably make it at diametrically opposite 80 points 13 in the concavity of the removable rim, see Fig. 5. Said flattening consists in a slight change in the form of the edge by changing a part of the sphericity of the segment into a cylindrical segment whose axis 85 passes through the center of the sphere and of the wheel, said cylindrical surface extending from the center of the edge of the rim transversely to the side of the rim in a case where there is only one spherical segment on said rim, but where there is a plurality of two or more smaller segments, extending from the inner edge of one of them to the outer edge, the circumferential length of said cylindrical portion being greater or 90 less as preferred; and it being obvious that the amount of the cut-out part will depend upon the angle that the rim can take with relation to the wheel body while it is being demounted. The flattening will be enough 100 so that when the removable rim is turned crosswise of the fixed rim (as far as adjacent devices may permit) it may be drawn across it and made to clear the convexity of the latter so that the outer rim may be easily 105 removed and just as easily replaced.

In Fig. 4 I show a straight clencher rim 7^a, made in one instead of two pieces, and thickened so as to provide an inner concave face 12^a which is of the shape of a segment 110 of a sphere, and which, when the rim is on the wheel, is normally in contact with the curved face 11^a, which is a metallic face carried on a wooden felly 18 attached to spokes 19, the removable rim and wheel body being held locked together by means of the bolts 20.

In another form shown in Fig. 6, there is a wooden felly 22 secured to spokes 29. On felly 22 is a metallic band having a face 27 120 which is a segment of a sphere. A ring 21 is fastened to the clencher sections 7 by means of wires 8, 8 and is provided with a spherical face 26, having a flattened part 28. A series of bolts 23 having heads 25 and 125 nuts 24 is used the same as in the other forms.

In my description I have laid emphasis upon the fact that the wheel and rim have interengaging spherical segments, but it will 130

be understood that I am not restricted to this sphericity of these parts, but any other segmental forms or shapes or curvatures may be adopted on other centers than those specified or otherwise provided only the same result is attained and there may be a great deal of breadth in the construction of the means for permitting demounting. I, therefore, reserve the right of varying the details of the invention within wide limits so long as the same are covered by the claims.

Having thus described my invention, what I claim as new and desire to secure by Letters Patent, is:

1. The combination of a wheel body having a peripheral face formed as a convex spherical segment, and a demountable rim having its inner edge formed as a concave spherical segment, and adapted to engage the wheel body, and means for securing the parts together.

2. The combination of a wheel body having its peripheral edge formed as a spherical segment, a rim having its inner edge formed also as a spherical segment, the two segments being concentric, and means for holding the said parts in position with the segmental faces in contact, said means consisting of bolts passing through the two parts.

3. The combination of a wheel body having a face formed as a spherical segment and a removable rim having also a face formed as a spherical segment, the two segments being concentric, and one segment having a flattened portion that enables said part to be cleared from its engagement with the other when turned crosswise for demounting.

4. The combination of a wheel body having at its periphery a plurality of convex segmental faces, and a rim having on the inside thereof a plurality of concave segmental faces corresponding with the faces

on the body, the corresponding members of each pair of segmental faces being concentric, and means for holding the rim and the body in position with the segmental faces in contact with each other.

5. The combination of a wheel body having a face formed as a spherical segment, and a demountable rim having also a face formed as a spherical segment, one of said spherical segments having a flattened cylindrical section whose axis passes through the spherical center and extends from the transverse center of the spherical segment to one edge.

6. The combination of a wheel body having a face formed as a spherical segment, a rim having its inner edge formed also as a spherical segment, the two segments being concentric, and one convex and the other concave, and one segment having a flattened part consisting of the segment of a cylinder whose axis passes through the spherical center and whose section extends from the middle point of said segment transversely toward one edge so as to allow the dislodgment of the removable from the fixed rim in demounting the parts.

7. The combination of a wheel body having a transversely curved face, and a removable rim having an inner transversely curved face engaging the body face, one of said faces having a cylindrical or flattened portion extending from the point of longest diameter in the curvature of the faces to one of the edges of said face, and securing means for holding the edges in contact with each other consisting of transverse bolts passing through openings in both the removable and fixed parts, said bolts having heads and nuts for tightly locking the parts.

In testimony whereof I affix my signature.

WILLIAM J. P. MOORE.
